(57) **CLAIM**

The ornamental design for an automobile lower bumper, as shown and described in FIGS. 1-5.

DESCRIPTION

FIG. 1 is a front perspective view of an automobile lower bumper attached to a vehicle, no part of the vehicle is claimed;

FIG. 2 is a perspective view of the automobile grille;

FIG. 3 is a front view of the automobile grille;

FIG. 4 is a top view of the automobile grille; and,

FIG. 5 is a left side view of the automobile grille (the right side view is a mirror of the left side view and is not shown). The broken lines are for illustrative purposes only and form no part of the claimed design.
